UNITED STATES PATENT OFFICE.

ALBERT E. GUY, OF TRENTON, NEW JERSEY, ASSIGNOR TO DE LAVAL
STEAM TURBINE COMPANY, OF NEW YORK, N.Y.

PUMP.

No. 820,778.

Specification of Letters Patent.

Patented May 15, 1906.

Application filed April 3, 1905. Serial No. 253,443.

To all whom it may concern:

Be it known that I, ALBERT E. GUY, of Trenton, Mercer county, New Jersey, have invented a new and useful Improvement in Pumps, of which the following is a specification.

The object of the invention is to permit a centrifugal pump to be driven at high speed by a steam-turbine or like motor. It is especially desirable to drive such a pump at high speed when a high pressure of discharge is required rather than mere quantity of outflow per given time. Thus, for example, high discharge-pressure is desirable in the feeding of steam-boilers. It is well known, however, that high-speed rotary fluid-impelling devices, such as centrifugal pumps, cannot work efficiently or properly because the velocity of the rotary impeller is so great that suction is imperfect. If, however, the liquid be delivered to the impelling device, under an initial pressure the difficulty is overcome. I accomplish this by combining with the impelling device an injector disposed on the suction side of said pump and acting upon the incoming liquid to increase the pressure thereof, also by employing a portion of the kinetic energy of the flow produced by the impelling device to increase the kinetic energy of the flow entering said device. It will of course be observed that the increased pressure of liquid delivered by the pump is gained at the expense of a portion of the discharge; but this condition is advantageous in view of the fact that it is high pressure of discharge which is sought for and by this device accomplished.

In another application for Letters Patent, Serial No. 253,444, filed simultaneously herewith, I have described and claimed, broadly, the combination of a pump and means actuated by a portion of the liquid delivered thereby for increasing the pressure of the liquid on the suction side of said pump.

My present invention is an apparatus embodying this combination in a construction in which the liquid from the delivery-pipe is delivered by the injector or injectors directly to the impeller or impellers and in which the injectors are formed and placed so as to effect such delivery.

In the accompanying drawings, Figure 1 is a vertical section of the pump on the line $x-x$

of Fig. 2 Fig. 2 is a section of the line $y-y$ of Fig. 1.

Similar characters of reference indicate like parts.

1 is the impeller-wheel. The shaft 2, on which said wheel is carried, is journaled in the walls of the casing 3 and is actuated by any suitable motor, (represented at 4). The impeller-wheel 1 is here shown as duplex and has two sets of blades 5 6 of relatively opposite pitch, so that when the wheel is rotated the liquid is drawn in at both ends of the wheel and delivered at its middle portion, as shown by the arrows. The pump-casing 3 has an annular chamber 7 surrounding the wheel and communicating with delivery-pipe 8 and also two side chambers 9 10, which communicate with the branches 11 12 of the inlet or suction pipe 13. The outlet ends of the chambers 9 10 are contracted, so as to have a diameter $a-b$ less than diameter $c-d$ of the inlet ends of the impeller-wheels, and are surrounded by annular chambers 14 15, which may be integrally formed with the casing. The internal diameter $e-f$ of the chamber-outlets is greater than the diameter $a-b$ of the ends of the inlet-pipes and equal to the diameter of the openings $c-d$. The chambers 14 15 connect with the delivery-pipe 8 by the pipes 16 17. The liquid from the delivery-pipe 8 at high pressure is forced through the pipes 16 17 to the chambers 14 15 and escapes directly into the wheel through the annular space surrounding the ends of the branch inlet pipes 11 12. The outlet ends of the branch pipe 11 and the surrounding outlet end of the chambers 9 therefore unitedly form injector delivering liquid to wheel-blades 5, and the outlet end of branch pipe 12 and the surrounding outlet end of chamber 10 also unitedly form an injector delivering liquid to the wheel-blades 6. The liquid coming from the delivery-pipe 8 imparts velocity to the liquid coming through the suction-pipe 13 and branches 11 12, and hence sufficient pressure to enable the impeller-wheels efficiently to operate despite their high speed.

I claim—

1. A pump, a casing therefor, an injector actuated by a portion of the liquid delivered by said pump and acting upon the liquid on the suction side thereof: the said injector being formed of the wall of said casing.

2. In a centrifugal pump, an impeller-wheel, a casing therefor, a suction-pipe, a delivery-pipe, a chamber with which said suction-pipe communicates, having a constricted outlet and delivering directly into said wheel, an annular chamber in said casing surrounding said constricted outlet, and a conduit connecting said annular chamber with said delivery-pipe.
- 10 3. In a centrifugal pump, an impeller-wheel having two sets of blades respectively of opposite pitch, a casing therefor, a suction-pipe, a delivery-pipe, chambers with which said suction-pipe communicates and having
- 15 4. In a centrifugal pump, an impeller-wheel, a casing therefor, a chamber in said casing communicating with the suction-pipe of said pump and having its outlet in proximity to said wheel, an annular chamber having an outlet surrounding said first-named chamber-outlet, and a conduit connecting said annular chamber with the pump-delivery.
- 20 4. In a centrifugal pump, an impeller-wheel and an injector actuated by a portion of the liquid delivered by said wheel having its outlet in proximity to and registering with said wheel-inlet, and constructed to increase the pressure of the liquid entering said wheel.
5. In a centrifugal pump, an impeller-wheel, a casing therefor, a chamber in said casing communicating with the suction-pipe of said pump and having its outlet in proximity to said wheel, an annular chamber having an outlet surrounding said first-named chamber-outlet, and a conduit connecting said annular chamber with the pump-delivery.

In testimony whereof I have signed my name to this specification in the presence of two subscribing witnesses.

ALBERT E. GUY.
